(57) **CLAIM**

The ornamental design for a display panel or screen with animated graphical user interface, as shown and described.

DESCRIPTION

FIG. 1 is a front view of a first image of a display panel or screen with animated graphical user interface showing our new design; and,

FIG. 2 is a front view of a second image thereof.

The subject matter in this patent includes a process or period in which an image changes into another image. The process or period in which one image transitions to another image forms no part of the claimed design.

The broken line showing of the display panel or screen illustrates the environment of the claimed design and forms no part thereof. The broken lines showing of portions of the computer generated image illustrate portions of the computer generated image which form no part of the claimed design.
